DESIGN FOR A DRESS

Mary Ranuzzi, New York, N. Y.

Application July 16, 1940, Serial No. 93,704

Term of patent 3½ years

To all whom it may concern:

Be it known, that I, Mary Ranuzzi, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design;

Fig. 2 is a rear view of Fig. 1, and

Fig. 3 is an enlarged view of the sleeve member of the dress.

The design is characterized by the combination on the specific dress disclosed of the specific embroidery on the detachable sleeve member in association with the embroidery on the back of the belt; as shown.

I claim:

The ornamental design for a dress, substantially as shown and described.

MARY RANUZZI.
